UNITED STATES PATENT OFFICE

2,600,227

FOLDING SIDES AND TOP AWNING

Nicholas L. Etten, Waterloo, Iowa

Application March 29, 1950, Serial No. 152,574

12 Claims. (Cl. 160—58)

This invention relates to awnings and particularly to a folding awning which may be extended over a window for shading it against light and heat, as well as protecting the open window against wind and rain, while at other times the awning may be collapsed and folded in a smaller, compact and rigid manner against the house for secure storage and to protect the window and awning against severe storm and weather conditions.

It is the particular object of this invention to provide an awning that may be extended above a window to shade the window under normal weather conditions and then may be folded into safe, smaller, compact, collapsed position above the window.

Another object is to provide a folding awning comprising a hinged combination of its several parts that permit the use of lighter gauge materials that may be formed into smaller inter-connected parts that combine in a stronger hinged structure to attain greater overall stiffness and strength at lower cost.

Another object is to provide a complete unitary awning that may be collapsed and packed in a small shipping container for warehousing and shipments at minimum cost.

And a still further object is to provide a simple mechanism to actuate the awning from open shading position into collapsed stored position and the reverse.

Other objects and benefits will be apparent from the following description and claims in which:

Fig. 1 is a front perspective view of my awning in open extended position;

Fig. 2 is a vertical sectional view taken on the center line of the awning as shown in Fig. 1 and showing the cord raising mechanism for raising the awning and showing in dotted outline the positions of the sections when in folded position;

Fig. 3 is a front perspective view of the awning in closed folded position and showing in dotted outline the position of the sections about halfway between the open and folded positions; and

Fig. 4 is a small, broken, front sectional view as it would appear on the section lines 4—4 of Fig. 2 showing the arrangement of the control or lifting cord of the awning.

Now referring to the drawings and at the outset to Figs. 1 and 2, I designate the three top sections by the numerals 10, 11 and 12 and the dual side sections by 13, 14 and 15. The top sections 10 and 11 are hinged together by a stiff piano-type hinge 16 and the top sections 11 and 12 by a similar hinge 17. The sides 13 and 14 are hinged to-

gether by the hinge 18 and the sections 14 and 15 by the hinge 19. It will be appreciated that there is no hinged connection between the top and side sections except by the dual swivel hinges 20 on the outside corners of the sections 15 and 12. The top section 10 as shown in Fig. 2 is a stationary section being held together by side stiffener straps 10-b along its outside edges. The section 10 is fixed to the window lintel by an angle element 21 fixed in a conventional manner to the window lintel by screws 23. In a similar manner the side sections 13 are held in position on the window frame by angles 22 as clearly shown in Fig. 3 and conventional screws 23.

Now referring to Figs. 2 and 4 on the insides of the outer side sections 15 are pull brackets 24 hingedly mounting breaking levers 26 pivotally mounted on the bracket 24 by pivots 25. Connected to the pivotal levers 26 are cords 27 extending over off center guide blocks 28 on the inner sides of the sections 15 which lead the cord 27 into lifting pulleys 29 as clearly shown in Figs. 2 and 4. It will be understood that tension exerted on the vertical sections of the cords 27 will pivot the breaking levers 26 in a clockwise direction that will have the effect of lifting the hinge 17 in the direction of the arrow A as shown in Fig. 2. Thus a pull on the cords 27 will have the effect of collapsably folding the sections 12 and 11 by reason of the pivotal hinges 20 on the outside corners of the section 12. The breaking of the hinge 17 in the direction of the arrow A effects an almost straight folding movement of the sections 11 and 12 as is clearly shown in Fig. 3. Continued pull on the cords 27 will deposit the folded sections 11 and 12 on top of the section 10 as clearly shown in Fig. 2. At the same time and in the same movement side sections 14 and 15 will be folded inside of the sections 13 as also shown at the right side of Fig. 3 and in dotted outline in Fig. 2. Thus it will be appreciated that the awning may be actuated into folded collapsed position as shown by the dotted outlines in Fig. 2, and thus will effectively resist wind storms and the like, as a folded awning over the window as shown in Fig. 2, while it protects the window against such storms. It will be appreciated that when the top and side sections are folded together as illustrated, they are in excellent form to resist winds and will stay in the folded position until released by manual reverse unfolding outward movement on the side sections 14 and 15. When the overcenter positions are released in this manner, the awning can be lowered into unfolded extended position as clearly shown in Fig. 1. It will thus be observed

that my folding awning cannot be readily collapsed without the upward movement of the lever 26 to break the hinge 17 in the direction of the arrow A in Fig. 2. Thus, the awning in extended position is amply able to resist ordinary storms because of the overcenter interlock of the hinge connections as above described. In a similar manner, the awning cannot be extended into lowered position until the overcenter position of the folded sections are overcome by manual movement on the side hinge sections 14 and 15 as described.

Now observing the folded position of the awning with the top sections folded as shown in dotted outline in Fig. 2, and the side sections being folded as shown in dotted outline in Fig. 2, and taking into consideration that the folded top and side sections are separately held in position by the screws 23 which preferably are mounted in a conventional bayonet joint to enable quick removal and installation, it will be understood that my awning can be easily and quickly broken down into three relatively small, flat sections composed of the folded top sections 10, 11 and 12, and the six folded sections 13, 14 and 15 to be mounted in a small flat container. Thus it will be understood that my awning can be collapsed in an easily installed condition in a very small shipping carton or case.

From the foregoing drawings and descriptions, it will be appreciated that I have constructed an awning that may be fabricated from small, light metal sections that are effectively reinforced by edge supports such as hinges and similar stiffener members. The complete awning may be fully fabricated into three main component parts that may be folded into a small shipping container that permits the complete awning to be readily and economically stored and shipped. When received by the householder, it may readily be assembled and installed with a minimum of skill and labor. Further, when installed and in position on the house, it provides a sturdy all-season awning that will resist the elements and provide a maximum of protection when in both open and closed positions.

Having thus described my invention, I now claim as new:

1. In an awning, a top composed of hinged sections foldable into compact laterally horizontal position, a pair of sides composed of hinged sections foldable into compact vertical positions at the sides of the awning, pulley means at the rear of the awning, and cord means connected to the forward part of the awning and trained over said pulley means to actuate the top and side sections into folded compact positions.

2. In an awning, a top composed of hinged sections foldable into compact horizontal position, a pair of sides composed of hinged sections foldable into compact vertical positions at the sides of the awning under the folded top, and cord means connected to forward and rear parts of the awning to actuate the top and side sections into folded compact positions.

3. In an awning, a top composed of at least three sections foldable into compact horizontal position, a pair of sides composed of hinged sections foldable into compact vertical positions at the sides of the awning, and cord means connected to forward and rear parts of the awning to actuate the top and side sections into folded compact positions.

4. In an awning, a top composed of at least three sections foldable into compact horizontal

position, a pair of sides each composed of at least three sections foldable into compact vertical positions at the sides of the awning, and cord means connected to forward and rear parts of the awning to actuate the top and side sections into folded compact positions.

5. In an awning, a top composed of at least three hinged sections, a pair of sides each composed of at least three sections foldable into compact vertical positions at the sides of the awning, pivotal connections between the outer top and side sections, cord slip means at the rear of the awning, and cord means connected to a forward part of the awning and trained over said slip means to actuate the top and side sections into folded compact positions.

6. In an awning, a top composed of at least three hinged sections, a pair of sides each composed of at least three sections foldable into compact vertical positions at the sides of the awning under the top sections, pivotal connections between the outer top and side sections, cord slip means at the rear of the awning and cord means connected to the forward side sections and trained over said slip means to actuate the top and side sections into folded compact positions.

7. In a foldable awning, a top comprising transversely hinged sections foldable into superposed compact relationship, a pair of allochiral side members each comprising hinged sections foldable into compact juxtaposed vertical relationship beneath said top, and means to actuate said top and side members into folded positions.

8. In a foldable awning, a top comprising transversely hinged sections foldable into superposed compact relationship, a pair of allochiral side members each comprising hinged sections foldable into compact juxtaposed vertical relationship beneath said top, a breaking lever pivoted intermediate its ends to the forward section of each side member, one end of each said lever being disposed adjacent the top to force a top section upwardly upon folding of the awning, and cord means connected to the other end of each lever to actuate the awning into folded position.

9. In a foldable awning, a top comprising a top comprising a plurality of sections, a transverse hinge connecting adjacent sections whereby an outer section is foldable into superposed relationship with the rear section, a pair of allochiral side members each comprising hinged sections foldable into compact juxtaposed vertical arrangement, means connecting at least one of said hinged sections to said outer top section, breaking levers mounted on the outer sections of said side members adjacent said top in position to elevate the outer of said transverse hinges when actuated, and cord means connected to said levers to actuate the same and move the top and side sections into folded position.

10. In a foldable awning, a top comprising transversely hinged sections foldable into superposed compact relationship, a pair of allochiral side members each comprising hinged sections foldable into compact juxtaposed vertical relationship beneath said top, means to actuate said top and side members into folded positions, and a pivotal connection between the outer top section and each outer side member section, and the top sections and side member sections being otherwise disconnected.

11. An awning comprising a top including a plurality of successively interconnected top panels foldable into superposed relationship, a pair

of sides each including a plurality of sections movable into juxtaposed vertical relationship beneath said top, means connecting said top and sides together for concurrent movement of said top panels and sections, and means for actuating said top and sides.

12. An awning comprising a fixed top panel, a pair of fixed side panels secured to said fixed top panel, a plurality of hingedly connected top panels foldable over said fixed top panel, a plurality of side panels retractible to positions between and in juxtaposed relation to said fixed side panels, and means connecting said retractible side

panels and said foldable top panels together for concurrent actuation thereof.

NICHOLAS L. ETTEM.
